UNITED STATES PATENT OFFICE.

ADELBERT A. DURKEE, OF STONEHAM, MASSACHUSETTS.

SHOE FORMER.

Application filed February 16, 1923. Serial No. 619,387.

My invention relates to a shoe former designed for insertion in a shoe after it has been removed from the last to maintain it in proper form during the final manufacturing operations and is an improvement of the former described and claimed in United State Letters Patent No. 1,489,745, issued to me April 8, 1924.

In the manufacture of shoes, there are a number of final operations after the shoe is removed from the last such as monogramming, cleaning, insertion of sock lining, treeing, repairing, dressing, brushing, etc., which operations are generally carried on in the treeing and packing room and all of which, since the shoe is no longer held in its correct form by the last, have a tendency to warp the shoe and to destroy its correct and attractive lines and fitting qualities. Frequently, the natural reaction of the stock under the finishing processes, especially in a thin-soled shoe, causes the toe of the shoe to turn upwardly, and the frequent handling of the shoe causes the sides to be spread apart and distorted. Again in shoes made of thin or soft leather small wrinkles appear due to the fact that the leather is not supported over a firm form or held under tension during the final processes, and when the leather is shrunk by the use of a hot iron to remove the wrinkles an objectionable fullness appears in the lining.

In general, these various final processes have the effect of distorting the shoe and destroying the correct form and style given it by the last causing the attractive appearance and lines of the shoe to be sacrificed and its salability detrimentally affected.

The main object of the invention is the provision of a shoe former adapted to hold the shoe under a longitudinal tension during the final manufacturing processes in order to preserve the correct form given to the shoe by the last.

Another object of the invention is the provision of a former capable of adjustment to fit different sizes and styles of shoes and provided with means for indicating said adjustments, so that the former can be returned to a previous adjustment for a certain style and size of shoe without requiring experimentation to get the best adjustment.

A further object of the invention is the provision of a former which exerts a pressure on two main axial lines in a shoe, one extending from the center of the heel seat to

the toe of the shoe and the other from a point below the center of the heel to the center of the cone of the shoe and both pressures being capable of independent adjustment.

An additional object is to secure a former of simple, efficient and cheap construction which may be easily and expeditiously placed in or removed from a shoe without injury thereto and without affecting the lines thereof.

Other objects of the invention will be more specifically set forth and described hereinafter.

My invention contemplates a former provided with expanding means whereby pressure is exerted longitudinally upon the front and rear portions of the shoe to straighten it and to cause the sides to close in. Preferably the pressure is exerted in a plane which passes longitudinally and centrally through the shoe and is approximately perpendicular to the sole. In its preferred form my invention contemplates a former comprising two overlapping members connected together in sliding engagement with expanding means between; one of said members being adapted to engage the heel portion of the shoe on a central line from the sole to the top of the upper and the other of said members engaging the toe, and carrying means for engaging the cone of the shoe in a central line.

One of the important features of my invention resides in the provision of means for exerting pressure along two main lines, one running from heel to toe, approximately parallel with the sole, and the other from the lower part of the heel to the cone of the shoe, obliquely to the first line. The pressure along the first line overcomes the natural reaction of the sole to turn upwardly when the shoe is taken off the last and the pressure on the second line throws up the cone and straightens and draws in the sides of the shoe. In addition to their independent actions, pressures exerted along these two lines also have a cooperative effect in restoring the correct lines to the shoe provided it has become warped.

Another important feature of my invention consists in providing a series of graduations for each line of pressure corresponding to the range of sizes of shoes. This feature results in a saving of time in adjusting the former to various sizes of shoes and at the

same time secures a uniform pressure for all sizes in any one style. When the former has been adjusted to one shoe of a certain style in order to secure the proper pressure for 5 the best results the adjustment of the former for other sizes of the same style may be made in accordance with the graduations without requiring experimentation, and thereafter, by making a record of the particular adjustment 10 for that style, the former may be accurately adjusted for that style whenever necessary without loss of time. Furthermore, since such correct adjustments are made before the former is placed in the shoe, 15 the distortion thereof by frequent insertions and removals of the former for adjustment is entirely obviated.

A further feature of my invention is its wide range of adaptability, due to the fact 20 that it is independently adjustable on two lines of pressure which permits the former to be applied with equal facility to low and high heeled shoes in which the two lines of pressure vary in the amount of divergence 25 and consequently in their relative adjustments.

In the drawings illustrating the preferred form of my invention, Figure 1 is a side elevation of a shoe former constructed in accordance with my invention and shown in a 30 position of use in a shoe outlined in broken lines; Fig. 2 is a side elevation of the former; Fig. 3 is a bottom plan view of the same; Fig. 4 is a cross-sectional view on line 35 4-4 in Fig. 2 looking from right to left; and Fig. 5 is a cross-sectional view on line 5-5 in Fig. 2 looking from right to left.

Referring to the drawings, illustrating one form of my invention, 10 designates a 40 toe member and 12 a heel member, which members may be made in any suitable form but preferably are constructed from stiff wire rod. The toe member 10 is straight and adapted to engage at its forward end the inner surface of the toe of the shoe; its rear end 14 being upturned to serve as a finger piece. The heel member 12 is also straight but at its rear end is turned upwardly and then downwardly to form a loop 16 serving 45 as a heel-engaging portion. The free end 18 of the loop 16 is bent reversely into a forward parallel relation with the heel member 12 to serve as a guide rod and at its end is fixedly connected thereto by a transverse 50 link 20.

The two members may be secured together in overlapping relation by any suitable means permitting free relative longitudinal movement and one such means is shown comprising two or more connecting links. Upon 60 the front end of the heel member 12 is fixed transversely a flat link 22 having a hole to receive loosely the forward end of the toe member 10; the link also serving as a guide 65 to hold the toe member against lateral move-

ment, without interfering with its free longitudinal movement relative to the heel member. On top of the rear end of the toe member is mounted a flat band or plate 24 bored near its rear end to receive the finger piece 14 and near its forward end to receive the toe member 10, and since these parts are in right angled relation to each other, the band 24 is held rigidly against tilting laterally. The forward end 26 of the band 24 is bent 70 at right angles to the main body of the band and is bored to receive loosely the heel member 12, and the rear end 28 is bent in a similar direction but provided with two holes to receive loosely the heel member 12 and the guide rod 18. As thus constructed the toe and heel members are capable of free relative movement one to the other in a longitudinal direction and all the parts are retained in substantially one plane by the connections 20, 22, 26 and 28.

Any suitable means may be provided for holding the former in an expanded position and one such means is shown comprising a helical spring 30 mounted on the heel member 12 and abutting at its forward end the connection 26 and at its rear end a collar 32 which is slidably movable on the member 12 but which may be secured in adjusted position by means of a right-angled 90 fastening member 34 threaded through the block and adapted to bear against the member 12. The outer arm of the member 34 furnishes convenient means for turning it with the fingers to release the block or to secure it in any adjusted position upon the heel member 12.

To facilitate the adjustment of the former to different sizes and styles of shoes before insertion therein, it may be provided with a series of graduations 36 corresponding in range to the range of length sizes of the shoes in which it is to be used. In the scale shown in the drawings which is adapted for women's shoes, the graduations run from two to ten inclusive, each representing a full length size of shoe. The scale 36 is preferably marked on a part of the heel member, such as the guide rod 18 where it can readily be seen, and in a position to cooperate with the connection 28 which is carried by and moves with the toe member 10. The graduations are so placed that when the collar 32 is adjusted at a certain graduation, the former, when inserted in a shoe of that particular size, will be compressed sufficiently to exert the normal pressure upon that shoe. That is, the graduations are so placed that the former when adjusted for a particular sized shoe is longer than that size and therefore is contracted when placed in the shoe against the pressure of the spring 30.

For exerting pressure upon the cone of the shoe, a cone member 38 substantially triangular in general outline and having a

curved edge 40 adapted to engage the cone of the shoe may be fixedly mounted in an upright position upon a band 42 in any suitable manner. This end may be accomplished by providing the band 42 with two longitudinal through and through openings to receive projections 44 formed on the lower edge of the cone member 38, the ends of these projections being swaged over on the 10 under side of the band 42 to hold the cone member in a position substantially perpendicular to the band as shown in Figure 5. The band 42 is slidably mounted upon the toe member 10 by having its forward end 15 46 bend downwardly at right angles to the body portion 42 and bored to receive loosely the toe member 10 and its rear end 48 bent in a similar manner and provided with three openings to receive loosely the toe member 20 10, the heel member 12 and the guide rod 18. The part 48 thereby serves as a connection to hold the three members 10, 12 and 18 in one plane and in proper alignment and the cone in an upright position in the same 25 plane with said three members.

As thus described the band and cone member slide freely upon the toe and heel members but any suitable means may be provided for adjusting it in position to exert a 30 resilient pressure upon the cone of the shoe. Preferably, means similar to that used for the toe and heel members is provided comprising a helical spring 50 mounted on the toe member 10 and abutting at its forward 35 end the part 46 and at its rearward end a collar 52 secured in adjusted position by a fastening member 54 operating in the same manner as the fastening member 34.

A table of graduations 56 on the toe 40 member 10 may be provided for the cone member but since the cone member is adjusted only for variations in style, this table may be limited to three graduations 16, 12 and 8 respectively from rear to front. After 45 the cone member has been adjusted for the style no further adjustment is required since it is fixed on the toe member and the length adjustment is taken care of in adjusting the relation between the toe and heel members according to graduations 36.

In the use of my invention, the former is intended to be adjusted as to length and cone pressure before being placed in the shoe. Normally the two springs 30 and 50 are of 55 sufficient strength to hold the former in extended position with the cone in a forward position as shown in Figure 2, the two springs in this situation not being compressed to any appreciable extent. When the former is inserted in a shoe, one finger is placed in the circular hole 60 in the cone member and the thumb upon the finger piece 14 and the former is then contracted lengthwise against the pressure of the two springs 60 and is inserted in the shoe without disturb-

ing its lines by stretching or warping it. It is removed from the shoe in the same manner. The fact that the former may thus be contracted in length to a very appreciable extent is an important consideration because 70 it permits the removal of the former from the shoe after the completion of the finishing operations without in any way or to any extent stretching the shoe or altering its final shape and lines. 75

In adjusting the former in the first instance to a shoe of a particular style and construction, it will be necessary to experiment on one shoe of that style and construction for the purpose of obtaining data as to 80 the amounts of pressure on both lines which are needed for securing the best results, but after that data has been obtained for one shoe, the former may then be adjusted to all other sizes of that type of shoe by merely 85 changing the adjustment of the collar 32 to the particular size, the cone adjustment remaining the same for all sizes.

For example in Figure 2, the former is shown as adjusted for a number two size 90 woman's shoe with the connection 28 registering with the graduation 2. These graduations are so placed, however, that the former is reduced in length when placed in a No. 2 shoe, as shown in Figure 1, in order to secure a normal longitudinal pressure, the spring 30 being compressed sufficiently to exert such a pressure upon the shoe. In case, however, more than normal pressure is required to secure the desired results in a 95 shoe, the former may be adjusted a half-size or a full size or even more higher up on the scale, and the collar 32 secured in such position. If, for instance, the collar be adjusted on the graduation marked 3, then 100 when the device is placed in a number two shoe, the spring 30 is compressed an additional full size on the scale and increased pressure results. It is apparent that any practical degree of pressure may be attained by such adjustment, and when the final adjustment has been made on one size whatever that may be, as noted in respect to the scale of graduations, the adjustments for all other sizes so far as the length is concerned are fixed. Having thus attained the 105 length adjustment for one shoe of a particular make, it may be recorded and thereafter no further experimentation is required for those conditions. 110

The cone adjustment is both independent of and dependent upon the length adjustment. In the first place, it is independent of the length adjustment because it is a style adjustment and dependent upon the height 115 of the heel of the shoe. As a rule the higher the heel of the shoe the further rearwardly the cone member is adjusted upon the former. Since the range of this adjustment is somewhat less than the range of the length ad- 120

justment, I have found that three graduations are generally sufficient for this scale and will furnish a sufficient criterion or guide for a wide range of styles. In the second place the cone adjustment is dependent upon the length adjustment in that it follows it. After the cone adjustment has been fixed for one shoe of a certain style it is fixed for all sizes of that style since the cone member is fixed in position upon the toe member and moves therewith to adjust itself to various lengths of shoes.

The correct cone adjustment is in the first instance secured in the same manner as the length adjustment by experimentation to attain the desired and necessary pressure upon the cone by the spring 50. After being determined for one shoe, preferably at the same time that the length adjustment is made, it is made for all sizes of that style and may be recorded for future reference.

It will be apparent from the foregoing that the provision of two scales of graduations is productive of important advantages in the use of shoe formers. After the adjustments have been determined for the various styles and makes of shoes, which is a comparatively simple matter, no further experimentation is required and a device may be instantly adjusted merely by reference to the recorded adjustments for that particular style and make. In addition to saving the time heretofore wasted in experimenting with each shoe, the former may be accurately adjusted before being placed in a shoe which is of importance since it reduces to a minimum the handling and distortion of the shoe. Furthermore, the general construction of the former and its susceptibility to being retracted permits its installation in a shoe without disturbing the correct lines given by the last.

Although, as stated above, the illustrated former is one designed for women's shoes, it can be applied to both men's and children's shoes by mere variations in size and by the provision of scales of graduations suitable for those classes and sizes of shoes. Neither have I attempted herein to set forth the various conditions of style and construction which may affect the adjustment of the former to particular kinds of shoes, since to one skilled in the art of shoemaking it will be at once obvious how to apply the former to suit all conditions met with in the shoemaking art and to secure the desired results.

In the use of my invention, I have found that in addition to securing a perfect shape and attractive lines in the finished product certain economies are attained in the finishing processes. For instance, the former straightens out the lining and prevents wrinkling thereof and in many shoes obviates entirely the necessity of ironing to eradicate wrinkles. Again, since a wide

range of adjustment and consequent pressure may be attained, it is possible to hold any shoe in correct position during the entire finishing processes, irrespective of the style of make and the kind of material used in its construction.

The importance of holding the shoe in correct form during the finishing processes cannot be overestimated because to a great extent its saleability depends upon whether or not its lines and general appearance is attractive. If the shoe is warped when the dressing is applied it will always remain in that condition because the dressing will retain in the shoe the general shape and lines which it has when the dressing is applied.

It is to be clearly understood that my invention is not to be limited to the particular form shown and described herein since it may be embodied in various other constructions within the purview of the following claims.

What I claim is:

1. A shoe former having, in combination, a toe member and a heel member in overlapping extensible relation, resilient means for holding said two members in extended relation, said means being adjustable to regulate the amount of pressure exerted thereby when the former is placed in a shoe, a table of graduations marked on said former for regulating the adjustment of said resilient means, a cone member carried by said toe member and resilient means for holding said cone member in forward position, said means being adjustable to regulate the amount of pressure exerted thereby when the former is in a shoe.

2. A shoe former having, in combination, a toe member and a heel member arranged in interlocked overlapping extensible relation, resilient means for holding said two members in longitudinally extended relation, said means being adjustable to regulate the amount of pressure exerted thereby when the former is placed in the shoe; a cone member carried by said toe member, resilient means for holding said cone member in forward position, said means being adjustable to regulate the amount of pressure exerted thereby when the former is in the shoe.

3. A shoe former having, in combination, a toe member and a heel member in longitudinally overlapping extensible relation, resilient means for holding said two members in extended relation, said means being adjustable to regulate the amount of pressure exerted thereby when the former is placed in the shoe, a table of graduations marked on said former for regulating the adjustment of said resilient means, a cone member carried by said toe member, resilient means for holding said cone member in forward position, said means being adjustable to regulate the amount of pressure exerted thereby when the former is in the shoe, a cone member carried by said toe member, resilient means for holding said cone member in forward position, said means being adjustable to regulate the amount of pressure exerted thereby when the former is in the shoe.

the amount of pressure exerted thereby when the former is in the shoe and a table of graduations marked on said former whereby the adjustment of said cone member may be 5 regulated.

4. A shoe former having, in combination, two members in overlapping extensible relation, resilient means for holding said two members in extended relation, said resilient 10 means being adjustable, a cone plate carried by one of said members, and resilient means for holding said cone member in a forward position, said last mentioned means being adjustable.

15 5. A shoe former having, in combination, two members in overlapping extensible relation, resilient means interposed between said two members for holding them in an extended relation, a cone member carried by one of 20 said members for exerting pressure along the central line only of the cone of the shoe and a spring for holding said cone member in a forward position, said spring being adjustable in position to suit various styles of 25 shoes.

6. A shoe former having, in combination, two members in overlapping extensible relation, compressible means for holding said two members in extended relation, a cone 30 member carried by one of said members for engaging the cone of the shoe, a collar mounted on said member, said collar being adjustable longitudinally on said member, and a spring for holding said cone member 35 in a forward position, said spring abutting at its forward end said cone member and at its rear end said collar.

7. A shoe former having, in combination,

two members interlocked in overlapping extensible relation, compressible means interposed between said two members for holding them in extended relation, said means being adjustable, a cone member mounted on the forward one of said two members, a helical spring mounted on said forward one of said 40 two members for holding said cone member in forward position, said spring being adjustable, and a scale of graduations marked on said forward one of said two members to serve as a guide for the adjustment of said 45 spring.

8. A shoe former having, in combination, a toe member, a heel member, means connecting said two members in overlapping extensible relation and expansible means for 50 forcing said members into expanded position, a cone member carried by said toe member and movable thereon and adjustable resilient means for holding said cone member 55 in a forward position.

9. A shoe former having, in combination, two skeleton members in overlapping extensible relation in substantially the same plane for stretching a shoe lengthwise to cause its sides to close in, compressible means 60 for holding said two members in extended relation, a cone-plate mounted on one of said members, a spring for holding said plate in a forward position to exert pressure along the central line of the cone of the shoe and 65 means for regulating the pressure exerted by said spring.

In witness whereof, I hereunto set my hand this sixteenth day of January, 1923.

ADELBERT A. DURKEE.
